UNITED STATES PATENT OFFICE.

RENÉ THURY, OF GENEVA, SWITZERLAND, ASSIGNOR TO THE COMPAGNIE
DE L'INDUSTRIE ELECTRIQUE, OF SAME PLACE.

TRANSFORMER FOR ELECTRIC CURRENTS.

SPECIFICATION forming part of Letters Patent No. 567,424, dated September 8, 1896.

Application filed February 3, 1896. Serial No. 577,866. (No model.)

To all whom it may concern:

Be it known that I, RENÉ THURY, electrician, a citizen of the Republic of Switzerland, residing at Geneva, Switzerland, have
5 invented certain new and useful Improvements in and Relating to Transformators for Electric Currents, of which the following is a specification.

The purpose of the invention is to realize
10 an industrial and economical transformation of a continuous current of constant volume having a variable number of volts into a current of constant potential adapted to be used in circuits for lighting or other purposes.
15 Heretofore this transformation has been made by currents of constant intensity and motors acting upon suitable secondary generators either directly by fixing the movable parts of the said motors and generators upon one
20 and the same axis or indirectly by means of transmission devices.

The aforesaid system is sometimes very advantageous, but it has some inconveniences which limit its applications and which I re-
25 move by means of my present invention. The said inconveniences are substantially the following ones: first, the very expensive in-
stallation; second, the rather low effect, and, third, the large dimensions required for the
30 machine.

This transformer involves only one inductor and one armature, the latter being formed of a winding of the well-known Pacinotti system as motor or primary winding and a wind-
35 ing of the drum system as generator (or sec-
ondary) winding and a regulator for con-
trolling the constant number of volts in the
secondary winding. The transformation of a
40 current of a constant number of amperes into
a current of a constant number of volts has
not been yet effected by means of only one ma-
chine having a single inductor, on account of
the special difficulties arising from the fact
45 that, both windings of the armature rotating
in the same magnetic field with the same
velocity, the electromotive force induced in
those windings are in the same relation to
each other as the number of conductors in
50 series on each winding. Consequently the
counter electromotive force of the primary

circuit becomes independent of the work pro-
duced by the secondary circuit. The work-
ing of the machine would be impossible with-
out a device by means of which only as much
work can be absorbed as corresponds with 55
the work produced by the secondary coil, that
is to say, by which the volts at the terminals of
the primary coil may be varied according to
the "watts" produced by the secondary coil,
though the electromotive force produced in 60
each conductor of the primary coil is sub-
stantially constant.

The case is therefore quite different from
that of the transformation of a current of
high or low tension and constant potential 65
into a current of a different number of volts
of constant potential which presents less
practical difficulties.

I have observed that the sole practical way
of varying the volts absorbed by the pri- 70
mary coil, without varying the electromotive
force produced in each of its windings, is to
vary the position of the primary brushes by
constructing the armature so as to practically
realize the said variable position of the 75
brushes without producing sparks. Accord-
ing to my invention this purpose is realized
by the following means: first, by proportion-
ing the number of ampere-turns of the in-
ductor and the number of ampere-turns of 80
the induced coil, so as to have the electro-
motive force of self-induction of one section
in the moment of leaving the collector-plates
practically annulled by the electromotive
force produced in the inductive coil; second, 85
by dividing the induced coil into a sufficient
number of divisions for reducing to a mini-
mum the difference of potential between two
consecutive plates of the collector. This
causes more or less of the windings to be 90
placed in opposition to one another, altering
thus the number of volts absorbed by the
primary winding.

I have found that it is possible to con-
struct a good transformer of currents of con- 95
stant number of amperes into currents of
constant number of volts in connecting the
primary brushes with a regulator or governor
formed, for instance, of a centrifugal regu-
lator or of a solenoid-regulator acting upon 100

the position of the brushes. The accompanying drawings show, for instance, the constructions thereof applicable to my invention.

The same construction may of course be used to produce the inverse effect.

In the drawings, Figure 1 is an elevation and partial section of a transformer of my system provided with a centrifugal regulator or governor. Fig. 2 shows a modification of the automatic regulating or governing device. Fig. 3 is a transverse section of a portion of the armature, showing the double coils. Fig. 4 is a partial elevation and section of the parts shown in Fig. 3, but more fully and perfectly illustrating the same. Fig. 5 is a side elevation, and Fig. 6 an elevation in larger size, of the means for partially turning and regulating the brush-carrier of the primary-winding system. Fig. 7 is a diagram in elevation of the circuits of the motor-winding primary coil, and Fig. 8 is a diagram in elevation of the circuits of the generator-winding secondary coil of the drum system.

In Fig. 8 the N and S pole pieces have been moved outward on a greater radius for clearness and so as not to conflict with the dotted lines.

On the base A of the machine there are mounted the two supports or standards A' and A² of the axis B, upon which are fixed the following parts: a sleeve C, carrying the armature; cylindrical pieces D with dovetailed circular grooves carrying the insulated connectors or arms E' of the secondary coil E; the secondary collector or ring of commutator-plates E^X, connected by means of blades e with the said connectors E', which are formed so as to work like the wings of a ventilator; the primary collector or ring of commutator-plates G^X, connected by means of wires G' with the primary winding G, and a bevel gear-wheel H, acting upon the regulator or governor by means of a corresponding gear-wheel H'.

To the support A² there is affixed an annular bearing-piece a², carrying the sleeve k of the brush-holder K of the secondary collector E^X.

To the support A' there is affixed an annular bearing-piece a, carrying the sleeve i of the brush-bearer I of the primary collector G^X, the position of the said brush-bearer I being regulated by the partial turning of the sleeve i upon the annular bearing-piece a. The said sleeve i is provided with gear-teeth i', acted upon by the pinion l', fixed on a shaft L, which carries a bevel-pinion l², which is alternately acted upon either by the bevel-wheel m' or by the bevel-wheel m² of the regulator.

The base A bears, further, an inductor O, that is excited at will either by the primary current or by a derivation of the secondary current, according to circumstances.

The sleeve C of the armature is provided with arms C', insulated by means of plate-pieces c of insulating material and to which

is fixed the lamellated core C^X of the induced coil.

As shown in Figs. 3 and 4, the armature is composed of a primary winding and of a secondary winding disposed according to quite different principles. The primary winding G is of the type of Pacinotti's ring, and is therefore located between the teeth of the lamellated core C^X. The secondary winding E is disposed according to the drum system on the circumference of the ring and without any connection with the said primary coil G. The perfect insulation of the primary circuit from the axis and metallic mass of the machine is obtained by means of the pieces of insulating material c, intercalated between the sleeve or hub C and the arms C'. The armature is combined with a magnetic shield interposed between the two coils and formed of a winding of iron wires P, surrounding an insulating-coating Q. The said iron wires P are further adapted to overcome the centrifugal force acting upon the primary coil and the insulating-coating Q. There is further provided an insulating-coating R, upon which the secondary coil E is disposed according to the usual drum system and provided with a protecting-coating W and an insulating-coating W', the connecting-blades E' with the rapid rotation of the armature causing circulation of air which effect the ventilation of the machine and also separating the two coils or windings on the two faces of the drum.

The above-mentioned magnetic shield has for its object, first, to secure a uniform field; second, to reduce to a minimum the parasitical currents which would otherwise occur in the pole-pieces with reference to the variations produced in the magnetic field by the teeth of the armature; third, to reduce the air-gap.

The regulator or governor is rotated, as already described, from the main shaft B by the bevel-gearings H H'. The regulator or governor acts upon the primary brush-holder I by means of the wheels m' or m² and the bevel-wheel l², shaft L, and pinion l' in partly turning to a greater or less extent the said brush-bearer I in either direction. The regulator puts the windings of the primary coil in opposition and reduces thereby the number of volts absorbed.

In the modification shown by Fig. 2 the centrifugal regulator or governor is replaced by a solenoid-regulator of sufficient strength as to directly control the secondary current. It is composed of a fixed solenoid S, connected to a derivation of the secondary current, which attracts with more or less force the iron core T, rotated by means of the gears H H' by the main shaft B. The rotation of the core T is transmitted to the brush-holder I by the wheels m' or m², acting on the wheel l², shaft L, and pinion l'.

By the diagram Fig. 7 is shown an illustration of the primary winding G of the lamel-

lated core C^x , the wires therefrom extending to the commutator-plates G^x and the brushes, the directions of the currents being shown by the arrows.

5 By the diagram Fig. 8 is shown an illustration of the secondary winding E of the drum system upon the surface of the armature and the arrangement thereof with the commutator-plates E^x to regulate the current. Thus 10 the speed of the transformer is maintained substantially constant, varying only in the quantity which is necessary to maintain the voltage of the secondary coil exactly the same independently of the number of amperes.

15 Having thus fully described my invention, I claim—

A machine for transforming a current of constant number of amperes into a current of constant number of volts or inverse charac-

terized by a single inductor, a single armature bearing on the one hand a motor-winding (primary coil) of the system Pacinotti, and on the other hand a generator-winding (secondary coil) of the drum system, a magnetic shield being interposed between the two coils of the armature and a regulator being provided for controlling the position of the primary brushes and volts absorbed by the primary coil according to the watts produced in the secondary coil, substantially as shown 20 25 30 and described.

In testimony whereof I have signed my name to this specification in the presence of two subscribing witnesses.
